PROPELLER ADJUSTING DEVICE FOR
MARINE MOTORS

Wayne L. Gee, Maple Lake, Minn.

Application June 26, 1941, Serial No. 399,797

5 Claims. (Cl. 115—17)

This invention relates to variable pitch marine propellers, and particularly to conveniently accessible adjustment or control mechanism closely associated with the driving mechanism and propeller blades for varying the pitch of said blades in a desired manner.

It is an object to provide a variable pitch propeller and adjustment and control mechanism therefor particularly adapted for use in marine motors of the outboard type and eliminating the use of shifting collars, forks or levers by provision of positive, preferably gear-connected, actuating elements controllable from a point adjacent the motor proper and above the gunwale of the boat.

A further object is the provision of mechanism of the class described combined in close working relationship with the oscillatory mounting and propeller shaft of usual outboard motors and constructed for quick control to vary and reverse the pitch of the propeller blades, and readily lockable in any of the positions of adjustment within the range provided.

These and other objects and advantages will be more apparent from the following description made in connection with the accompanying drawing, wherein like reference characters refer to the same parts throughout the several views, and in which:

Fig. 1 is a view partly in side elevation and partly in vertical section, showing an outboard motor having an embodiment of my invention applied thereto;

Fig. 2 is a cross section taken on the line 2—2 of Fig. 1, showing a connection between the longitudinally movable actuating member and the variable pitch blades of the propeller;

Fig. 3 is a cross section taken on the line 3—3 of Fig. 2;

Fig. 4 is a cross section taken on the line 4—4 of Fig. 1, showing the enlarged bearing for the tubular post and manipulating lever, and

Fig. 5 is a cross section taken on the line 5—5 of Fig. 1.

As shown in the drawing, my improved mechanism is applied to an outboard motor constructed for the most part of conventional form having the motor proper including a cylinder C, fly wheel F, gas tank T and other working parts of the motor mounted on the top of a tubular post P through which the vertical driving shaft 7 axially extends and is connected at its upper end with the crank shaft of the motor. The outboard motor shown is provided with an underwater unit U of conventional shape for effi-

ciently cutting and displacing the water and constituting a housing for certain of the working parts, including a driving connection between the driving shaft 7 and the horizontal propeller shaft 8 housed therein. The lower and horizontal portion of underwater unit U is of torpedo shape having a pointed nose and, as shown, a rear end tightly closed by a bearing plug 9. The water supply pipe 10 for the cooling system of the engine extends upwardly from an intake neck 11 having a conventional type of water pump mounted therein, the pump being secured to a horizontal plate 12 affixed to the upper end of unit U. Water pipe 10 extends substantially parallel with the post P and passes through sleeves 19 and 20 affixed to said post, and is connected at its upper end with the water jacket of the motor.

Tubular post P rigidly connected at its lower end with the underwater unit U, is mounted for oscillation in an enlarged bearing sleeve 13 which is rigidly connected or integrally formed with a heavy arm 13a pivotally connected by a nutted bolt 14 with the upper end of a motor attachment bracket 15 of yoke formation. The sleeve 13, and with it the entire motor, tubular shaft P and underwater unit, is swingable on the horizontal axis of bolt 14. Yoke bracket 15 is provided with the conventional clamping faces 15a for engagement with the outer surface of the stern board of a boat, and the usual clamping bolts 16 cooperate with the bracket by threaded engagement with a pair of tapped lugs 15b integrally formed with the bracket proper and spaced inwardly from the clamping surfaces 15a. The yoke bracket 15 has at its lower portion, spaced, sector-shaped stop-retaining arms 15c slotted accurately concentric of the pivot bolt 14 for receiving a nutted clamping bolt 17 which secures an abutment plate 18 of conventional type for engaging an enlarged sleeve 19 rigidly connected with the intermediate portion of tubular post P in such position as to engage said abutment. The upper portion of post P is provided with a second enlarged sleeve 20 flanged at the upper and lower ends thereof and fitting the supporting bearing sleeve 13 with working clearance for oscillation.

Propeller shaft 8 in the embodiment shown is tubular, being journalled in the plug bearing 9 which closes the rear end of the lower torpedo portion of the underwater unit U. The tubular propeller shaft 8 has affixed to the rear portion thereof, within the housing of unit U, a bevelled driven gear 8a which is constantly meshed with

the driving gear $7a$ fixed to the lower end of the vertical driving shaft 12 . The propeller unit is rearwardly and axially mounted on the bearing cap 9 comprising a symmetrical hollow hub 21 wherein mechanism for varying the pitch of the propeller blades 22 is mounted. Propeller blades 22 are mounted for oscillation by means of axially extending shanks $22a$ which are journaled in tapped bearings cast or otherwise integrally formed with the hub structure, the blades projecting from opposite sides of hub 21 with their shanks $22a$ disposed in parallel spaced arrangement carrying gear pinions $22b$, said pinions $22b$ being opposed and spaced apart for reception of and driving connection with a cylindrical rack rod or actuating connection 23 . Actuating connection has its outer end slidably journaled in a tapped stud cap 24 threadedly engaging and closing the outer end of hub 21 . The medial portion of said rod 23 is telescopically mounted within the tubular propeller shaft 8 extending therethrough and having its forward portion slidably journaled in the tapped forward end of the torpedo portion of the unit U . As shown, the tubular propeller shaft 8 is connected to drive the propeller hub 21 by means of a shear pin set screw 25 , although any other suitable connecting means may be utilized. The portion of actuating rod 23 between the forward end of propeller shaft 8 and the forward extremity or slide portion of the rod is constructed in similar manner to the rack rod portion $23a$ at the rear thereof, the rod being provided with a series of rounded annular flanges $23b$ spaced apart to nicely mesh with an adjustment pinion $26a$ which is fixed to the lower end of upstanding adjustment shaft 26 , said shaft passing through a suitable packing gland $26c$ at the top of the housing U and extending upwardly through an aligned bore formed in sleeve 19 and a second aligned bore $20a$ formed in the upper retaining sleeve 20 of the tubular post. The upper end of adjustment shaft 26 is provided with a radially extending handle $26b$ which may be, as shown, integrally formed therewith, said handle being disposed just below the steering arm S of the outboard motor in convenient position to be manipulated. Shaft 26 and the handle $26b$ are detachably locked in any one of a number of various radial positions by suitable means such as a retaining sector 27 fixed to the sleeve 13 and having retaining notches on the upper edge thereof opposed to said handle.

In operation, with the motor running, the propeller is driven by means of the connection of hub 21 with the tubular propeller shaft 8 . The outer end of the bearing cap 9 at the rear of the underwater unit acts as a thrust bearing for the opposing end of the propeller hub and the bevel gear $8a$ is constantly meshed with the bevel gear $7a$ at the lower end of the driving shaft 12 .

For full forward speed the controlling handle $26b$ is conveniently set at one extreme position, turning adjustment shaft 26 , which through its pinion connection with the actuating rod 23 tilts propeller blades 22 to the most efficient angle for forward travel of the boat. Adjustment shaft 26 and the propeller blades are maintained in the desired adjusted position by retention of the handle $26b$ in the appropriate notch of the retaining sector 27 . Propeller blades 22 may be adjusted to various pitch positions between full speed forward position and most efficient reverse positions by swinging handle $26b$ and setting the

same in the various positions within the range provided by sector 27 . In the intermediate positions, the speed of the boat may be slowed down as desired for trolling or extremely slow movement, and all shifting and adjustment may be accomplished, of course, while the motor is running. It will be noted in my construction that no levers or shipper forks are provided for making actuating connection between the adjustment shaft and variable pitch propeller blades. My longitudinally movable actuating rod is at all times positively connected with the adjustment shaft 26 and with the pinions $22b$ of the propeller blades. Adjustment shaft 26 is properly positioned and journaled in the tapped bearings provided in the sleeves 13 and 19 fixed to tubular shaft P .

It will be seen that the outboard motor may be swung for steering in conventional manner without in any way interfering with the adjustment or operation of my mechanism, and that further the entire motor and underwater unit may be tilted on the horizontal axis of bolt 14 to avoid obstructions or elevating the underwater unit when the boat is beached. The construction of the actuating connection or rack rod 23 with the fillets or spaced annular rack flanges, provides a highly efficient actuating connection between the adjustment shaft and variable pitch propeller blades, minimizing the wear of the connecting parts and making it possible for rod 23 to turn from friction without undue wear or fracture of the parts.

It will, of course, be understood that various changes may be made in the form, details, arrangements and proportions of the parts without departing from the scope of my invention.

What is claimed is:

1. In outboard motor construction of the type having a tubular post, a motor at the upper end thereof and an underwater unit at the lower end thereof and a propeller shaft journaled in said underwater unit; variable pitch propeller mechanism comprising a longitudinally shiftable actuating member mounted in said underwater unit concentrically with said propeller shaft, a propeller having a plurality of blades mounted for oscillation, actuating connections between said blades and said actuating member, an adjustment shaft extending upwardly from said underwater unit to the top of said post, said adjustment shaft having toothed driving engagement at its lower end within said unit with said actuating member for longitudinally shifting the same, and means at the upper end of said shaft for facilitating rotation thereof to adjust the pitch of said blades.

2. In outboard motor construction of the type having a tubular post, a motor at the upper end thereof and an underwater unit at the lower end thereof and a propeller shaft journaled in said underwater unit; variable pitch propeller mechanism comprising a longitudinally shiftable actuating member mounted in said underwater unit concentrically with said propeller shaft, a propeller having a plurality of blades mounted for oscillation, actuating connections between said blades and said actuating member, an adjustment shaft extending upwardly from said underwater unit to the top of said post, said adjustment shaft having toothed driving engagement at its lower end with said actuating member for longitudinally shifting the same, said tubular post having a radially enlarged journaled portion adjacent its upper end, means for pivotally mount-

ing said journalled portion with freedom for oscillation of said post and said motor and underwater unit therewith, said journalled portion having a longitudinal bearing extending therethrough in which the upper portion of said adjustment shaft is mounted, and means at the upper end of said shaft for facilitating rotation thereof to adjust the pitch of said blades.

3. The structure set forth in claim 2, said adjustment shaft extending through the upper end of said underwater unit in parallel relationship with and outside of said tubular post, and means for retaining said shaft in a multiplicity of different adjusted positions.

4. In outboard motor construction of the type having a tubular post, a motor at the upper end thereof, a driving shaft mounted within said post, an underwater unit secured to the lower portion of said post and a propeller shaft journalled in said underwater unit and drivably connected with said driving shaft; variable pitch propeller mechanism comprising an actuating rod mounted in said underwater unit concentrically with said propeller shaft, a propeller having a hub and a plurality of blades having shanks mounted for oscillation in said hub, said shanks each having a pinion fixed thereto, said pinions being disposed in an orbit, said actuating rod having a series of longitudinally spaced circular rack elements meshed with said several pinions

for oscillating said blades, an adjustment shaft extending upwardly from said underwater unit in substantially parallel relationship with said driving shaft, said adjustment shaft having a pinion fixed to the lower portion thereof within said unit, said actuating rod having a series of longitudinally spaced circular rack elements meshed with said adjustment pinion within said unit, and means at the upper end of said adjustment shaft for facilitating oscillation thereof.

5. In outboard motor construction of the general type having a tubular post, a motor at the upper end thereof and an underwater unit at the lower end thereof; variable pitch propeller mechanism comprising, a propeller shaft journalled in said underwater unit, a longitudinally shiftable actuating member mounted within said underwater unit concentrically of said propeller shaft, a propeller having a plurality of blades having shanks journalled transversely of said propeller shaft, said shanks having toothed connection within said underwater unit with said longitudinally shiftable actuating member to oscillate said blades, and an adjustment shaft extending upwardly from said underwater unit and having a pinion affixed to the lower portion thereof within said unit, said actuating member carrying a rack in mesh with said pinion.
